UNITED STATES PATENT OFFICE

THOMAS HUGH PARKER, OF BOSHAM, ENGLAND

SOUND REPRODUCING MECHANISM

Application filed January 20, 1930, Serial No. 422,198, and in Great Britain January 21, 1929.

This invention relates to vibration transmitting arms for use in sound reproducing mechanism.

The object of the present invention is to produce a vibration transmitting arm which while having the necessary rigidity is very flexible and permits of a large magnification of the vibrations transmitted.

According to this invention the vibration transmitting arm consists of a circular ring of thin flexible metal having an arm extending both inwardly to the centre of the ring and outwardly for a short distance beyond the periphery of the ring.

The ring is of approximately the same diameter as the sound box, pick-up, loud speaker or ear phone to which it is to be applied and is secured thereto. The inner end of the arm is secured to the diaphragm of the sound reproducer, and the outer end is secured to the part which sets up the vibrations to be transmitted.

The ring of metal is insulated from the casing of the sound box, pick-up, loud speaker or ear phone, to which it is secured, by means of rubber or other resilient packing.

The device can be used as the stylus arm of a gramophone sound box, the stylus being secured to the outer end of the arm and the inner end of the arm being secured to the centre of the diaphragm, the ring part being secured to the sound box casing. Or, if it is to be used with a loud speaker, the outer end of the arm would be secured to the armature of an electric-magnet, the inner end of the arm being secured, as before, to the diaphragm of the loud speaker, the ring part being secured to the loud speaker unit.

My invention is illustrated in the accompanying drawing in which Fig. 1 shows the vibration transmitting arm in plan view adapted for use as the stylus arms of a gramophone. Fig. 2 is a detail transverse section of a sound box provided with my improved vibration transmitting arm.

As shown the arm consists of a circular ring 1 of thin flexible metal having an arm extending inwardly to the centre of the ring as at 2 and outwardly for a short distance beyond the periphery of the ring as at 3.

The inner end 2 of the arm is provided with means (not shown) for securing it to the centre of a diaphragm, and the outer end 3 of the arm is provided with a hole for the insertion of the stylus 4, and a screw 5 for holding same in position.

The ring 1 is secured, between rubber or other insulating resilient packing, to the sound box casing indicated at 6 by screws or other suitable means.

I claim:—

A vibration transmitting device, for use in sound reproducing mechanism, consisting in combination with a sound box of a ring of thin flexible metal arranged in the sound box and having an arm extending both inwardly to the centre of the ring and outwardly for a short distance beyond the periphery of the ring and made in one piece with the ring, said ring being secured to the sound reproducing mechanism.

In testimony whereof I have hereunto set my hand this 8th day of January, 1930.

THOMAS HUGH PARKER.
